CLAIM

The ornamental design for a combination ceiling fan and light fixture, as shown and described.

DESCRIPTION

FIG. 1 is a perspective view of a combination ceiling fan and light fixture in accordance with my design;

FIG. 2 is a top plan view of the combination ceiling fan and light fixture in accordance with my design;

FIG. 3 is a bottom plan view of the combination ceiling fan and light fixture in accordance with my design;

FIG. 4 is a front elevation view of the combination ceiling fan and light fixture in accordance with my design;

FIG. 5 is a rear elevation view of the combination ceiling fan and light fixture in accordance with my design;

FIG. 6 is a left-side elevation view of the combination ceiling fan and light fixture in accordance with my design; and,

FIG. 7 is a right-side elevation view of the combination ceiling fan and light fixture in accordance with my design.

The broken-line disclosure of elements is understood to represent portions of the article in which the design is embodied, but which form no part of the claimed design.

1 Claim, 5 Drawing Sheets
